UNITED STATES PATENT OFFICE.

WILFRID BOULAIS, OF IPSWICH, MASSACHUSETTS.

YARN-RELEASING DEVICE FOR SPOOLS

1,081,716.

Specification of Letters Patent. Patented Dec. 16, 1913.

Application filed February 28, 1913. Serial No. 751,290.

To all whom it may concern:

Be it known that I, WILFRID BOULAIS, a citizen of the United States, residing at Ipswich, county of Essex, State of Massachusetts, have invented an Improvement in Yarn-Releasing Devices for Spools, of which the following description, in connection with the accompanying drawing, is a specification, like characters on the drawing representing like parts.

This invention has for its object to provide a yarn-releasing device to facilitate the unwinding of yarn from spools.

It is capable of use in connection with any machine where yarn is fed from a spool, as, for instance, a knitting machine or a braiding machine, and is particularly designed to be used in connection with yarn or thread of that character which is more or less rough and is likely to have kinks or knots therein. Silk or artificial silk is an example of thread or yarn having the above characteristics.

In knitting machines in which a silk thread is being knit into the fabric, such silk thread is usually delivered from a spool on which the thread is wound, said spool being supported in a stationary spool support in such a way that the thread is drawn off over the end of the spool. A silk thread and especially a thread of artificial silk is apt to have some knots or kinks in it, and further it has the characteristic that the adjacent coils or turns of the thread on the spool are apt to adhere or stick together somewhat. Where a silk thread of this nature is drawn off from the end of a spool in a knitting machine or machine of similar character, the adhesion of the turns or coils of the thread to each other and the tendency of any knots in the thread to catch on and adhere to the other coils of the thread is sometimes sufficient to cause the thread to become broken. It is to avoid this difficulty that I have made my invention, and it comprises a thread-releasing and guiding member which acts on the thread as it is being delivered from the spool and not only releases the turns of the thread progressively from the spool, but obviates the danger of breakage of the thread due to catching of a knot therein on the end of the spool or adjacent coils of thread.

In the accompanying drawings wherein I have illustrated a selected embodiment of my invention, Figure 1 is a side elevation, partly in section showing my improvements; Fig. 2 is a plan view.

In Fig. 1 I have shown at 1 a spool support on which is supported a spool 2 having the thread 3 wound thereon. The spool 2 is held stationary on the support 1, said support having the central hub 4 which extends up into the opening in the spool 2. Associated with the spool support is a guide eye 5 through which the thread 3 is drawn, said eye being supported on a suitable arm 60 and sustained in line axially with the spool.

Where this device is used in connection with a knitting machine the yarn is led from the guide eye 5 directly to the yarn feed and needles of the knitting machine. The thread is thus drawn off from the end of the spool. In order to facilitate this operation without danger of breaking the thread I employ a thread-guiding member 6 which is herein shown as having a bell shape and which is supported above the end of the spool between the latter and the guide eye 5. This thread-guiding member has a smooth rounded exterior surface and has a greater diameter than that of the spool. It is sustained for rotation in the direction in which the thread is being unwound from the spool. As herein shown the thread-guiding member is provided with a hub 7 which fits upon a spindle 8. This spindle 8 extends axially through the spool 2 and is freely rotatable in bearings 9 formed in the spool support 1. The spindle has fast thereto a gear 11 which is confined in the chamber 10 in the spool support and means are provided for positively rotating this gear in the direction in which the yarn is unwound from the spool 2. While any suitable rotating means may be employed that herein shown comprises a second gear 12 journaled in an extension 13 of the spool support and meshing with the gear 11 and having rigid therewith a bevel gear 14 which meshes with and is driven by a bevel gear 15 on a shaft 16. This shaft 16 leads to and is driven by some suitable operating part of the machine with which my invention is to be used. If this invention is to be used in connection with a knitting machine, then the shaft 16 will be connected to and driven from some rotating part of the knitting machine. I will preferably inclose the gears in a casing so that they may be kept thoroughly lubricated.

In the operation of the device the thread-guiding member 6 is rotated positively in the direction in which the thread is being

unwound from the spool and as the thread is drawn from the spool through the guide eye 5 it passes around and has frictional engagement with the exterior surface of the 5 thread-guiding member. For instance, in Fig. 2, if the thread is being unwound from the spool in the direction of the arrow *a* then the thread-guiding member 6 will be driven in the same direction as indicated by 10 the arrow. The speed of rotation of this thread-guiding member will preferably be greater than the speed at which the thread is unwound, so that the frictional engagement between the thread and the thread-guiding 15 member will tend to unwind the thread from the spool. I have found that by providing this rotating device which is positively driven, as above described, and has the frictional contact with the thread, the thread 20 will be unwound from the spool without any danger of its becoming broken, due to a knot therein catching on any adjacent coils or turns of the thread.

With my device it is possible to use thread 25 which is rather rough and imperfect without danger of its becoming broken in being drawn off from the spool.

The important feature of the invention is the provision of means for positively rotating the thread-guiding member at a speed at 30 least as great as and preferably greater than that at which the thread is unwound from the spool.

Having now fully described my invention what I claim as new and desire to secure by 35 Letters Patent is:—

1. In a device of the class described, the combination with a stationary spool support, of a spool sustained thereby, a guide eye situated in line axially with the spool, a 40 rotatable annular guiding member of greater diameter than the spool situated axially of and adjacent one end of the spool and over which the thread passes from the spool to the guide eye, and means to rotate positively 45 said guiding member in the direction in which the thread is unwound from the spool.

2. In a device of the class described, the combination with a stationary spool support, of a spool sustained thereby, a guide 50 eye situated in line axially with the spool, a rotatable annular guiding member of greater diameter than the spool situated axially of and adjacent one end of the spool and over which the thread passes from the spool to 55 the guide eye, and means to rotate said guiding member in the same direction as but at a greater speed than the thread which is unwound from the spool.

In testimony whereof, I have signed my 60 name to this specification in the presence of two subscribing witnesses.

WILFRID BOULAIS.
